UNITED STATES PATENT OFFICE.

WILLIAM M. BRADSHAW AND WALTER G. MYLIUS, OF WILKINSBURG, PENNSYLVANIA,
ASSIGNORS TO WESTINGHOUSE ELECTRIC AND MANUFACTURING COMPANY, A COR-
PORATION OF PENNSYLVANIA.

PREPAYMENT WATT-HOUR METER.

1,321,506.

Specification of Letters Patent.

Patented Nov. 11, 1919.

Application filed March 17, 1916. Serial No. 84,860.

To all whom it may concern:

Be it known that we, WILLIAM M. BRADSHAW, a citizen of the United States, and a resident of Wilkinsburg, in the county of

5 Allegheny and State of Pennsylvania, and WALTER G. MYLIUS, a citizen of the United States, and a resident of Wilkinsburg, in the county of Allegheny and State of Pennsylvania, have invented a new and useful
10 Improvement in Prepayment Watt-Hour Meters, of which the following is a specification.

Our invention relates to watthour meters of the prepayment type and particularly to
15 detachable unitary coin-controlled devices for such meters.

One object of our invention is to provide a detachable coin-controlled device that may be quickly and easily substituted for
20 the integrating mechanism of an ordinary watthour meter to constitute a prepayment meter.

Another object of our invention is to provide a coin-controlled device of the
25 above indicated character that shall have means for holding the coin in a gripped position until it has been turned a predetermined distance.

Another object of our invention is to provide a coin-controlled device of the above indicated character that shall have means for easily disconnecting its controlling device from its main spring to facilitate testing of the device.

35 Another object of our invention is to provide a coin-controlled device of the above indicated character that shall have means for interrupting the circuit of the meter windings when its main spring has been unwound a predetermined amount, irrespective of its relative positions.

Another object of our invention is to provide a coin-controlled device of the above indicated character that shall have means for closing its coin slot when its main spring has been wound a predetermined amount, irrespective of its relative positions.

Another object of our invention is to provide a cover plate for a meter of the above

indicated character that shall have means for so supporting a coin receptacle that the extraction of coins is precluded when the cover is removed.

Our copending U. S. application, Serial 55 No. 873,924, filed November 25, 1914, discloses a prepayment meter having a main spring that is adapted to be wound from one end and to be unwound from its other end to control the operation of a switch. In 60 our present invention, we embody some of the novel features of the above indicated application in a unitary coin-controlled device that is adapted to be detachably connected to an ordinary wattmeter to constitute a prepayment meter. The unitary coin-controlled device is so constructed that its switch is adapted to be tripped when its main spring has been unwound a predetermined amount, irrespective of its relative positions when such unwinding obtains. The coin slot of the coin-controlled device is adapted to be closed when the main spring has been wound a predetermined amount, and means is provided for holding a 70 coin in its operative position until it has been turned to a predetermined position.

In the accompanying drawings, Figure 1 is a front elevational view of a prepayment watthour meter embodying our invention; Fig. 2 is a front elevational view of the meter shown in Fig. 1, with the cover removed; Fig. 3 is a side view, partially in elevation and partially in section, of the meter shown in Figs. 1 and 2; Fig. 4 is a 80 side view, partially in elevation and partially in section, of a detachable coin-controlled device embodying our invention; Fig. 5 is a front elevational view, with parts broken away, of the coin-controlled 85 device shown in Fig. 4; Fig. 6 is a bottom plan view, with parts broken away, of the coin-controlled device shown in Figs. 4 and 5; Fig. 7 is a rear elevational view of the coin-controlled device shown in Figs. 4, 5 95 and 6; Fig. 8 is a detail view of a lever having two spaced-apart arms that are employed in the coin-controlled device, and Figs. 9 and 10, and 11 and 12 are front and side elevational views, respectively, of the 100

two plates of the coin gripping device embodying our invention.

A prepayment watthour meter 1 comprises an ordinary watthour meter 2, a 5 unitary detachable coin-controlled device 4 and a cover 5.

The watthour meter 2 comprises a casing 3 in which a magnetizable core member 6, magnetizing windings (not shown), a 10 rotatable armature 7 that is mounted on a shaft 8 and a plurality of damping magnets 9 are mounted. The casing 3 is provided with a magnet support 10 that is adapted to support the coin-controlled device 4. The watthour meter 2 is of the ordinary induction type and may be constructed substantially in accordance with what is set forth in U. S. Patent No. 853,226, issued May 14, 1907 to F. Conrad and William Bradshaw, and assigned to the Westinghouse Electric and Manufacturing Company. However, any other suitable form of wattmeter may be used if sufficient room is provided to substitute the unitary coin-controlled device 4 for the integrating mechanism.

The cover 5 is constructed of stamped and pressed material and is provided with two windows or openings 11 and 12. A substantially semi-cylindrical member 13, that is also constructed of stamped and pressed material, is attached to the outer surface of the cover 5 in any suitable manner, such, for example, as spot welding or riveting. 35 The member 13 is open at its lower end 14 to receive a coin receptacle 15. The member 13 is enlarged, near its upper end 16, to receive a portion of the coin-controlled mechanism and is provided with a coin slot 17. 40 Deflecting plates 18 and 19 are so disposed within the member 13 that, when the cover 5 is removed from the base 3 by removing fastening screws 20, the coins in the receptacle 15 cannot be extracted. A retaining 45 bar 21 is inserted in openings in the walls of the member 13 to retain the coin receptacle 15 in position and may be provided with any suitable form of lock (not shown).

The coin-controlled device 4 is mounted 50 on a plate 22 that is secured to the magnet-supporting frame 10 by screws 23 and comprises, in general, a switch 24, an escapement mechanism 25, a main spring 26 and a coin device 27.

55 The coin device 27 is mounted on the plate 22 and comprises a casing 28 that is provided with openings 29 and 30. A knurled head knob 31 is mounted on a relatively short shaft 32 that extends through 60 one end of the casing 28 and is provided with a spring 33 for returning it to its normal position after it has been turned a predetermined distance. A plate 34 is mounted on one end of the shaft 32 and is 65 provided with a flanged periphery 35 and

with two eccentric coin-positioning flanges or projections 36. The flanged edge or periphery 35 is cut away over a portion of its length to permit an unobstructed opening from the coin slot 17 through the opening 29 in order that a coin 37 may pass therethrough and rest upon the flanges or projections 36. A second plate 38 is mounted on one end of the main shaft 39 of the coin-controlled device 4. The plate 38 75 is provided with two curved flanges 40 and 41 that are of such size and are so positioned as to extend between the flanged edge or periphery 35 of the plate 34 and the projections 36. Thus, when the plate 34 is 80 turned, and a sufficiently large coin 37 is resting on the projections 36, the flanges 40 and 41 will so grip the plates 34 and 38 together that the shaft 39 may be turned. Two resilient members 42 and 43 are mounted on the plate 38 and have inclined portions that are adapted to coöperate with a stationary pin 44 to hold them in such position when the plates 34 and 38 are turned, that, when the knurled head knob 31 has 90 been turned exactly 180° the members 42 and 43 will disengage the pin 44 and return substantially to the position shown in Figs. 3 and 4 of the drawings to permit the coin to drop into the receptacle 15. The 95 plate 34 is provided with a stop 45 that coöperates with a corresponding stop (not shown) in the casing 28 to permit the knurled head knob 31 to be turned through 180° only. By such an arrangement, the 100 main spring 26 is wound a predetermined constant amount for each coin inserted in the device. Whereas, in other prepayment meters there was a likelihood that the coin would be dropped into its receptacle before 105 it had permitted the spring to be wound the required amount. In our device, when the knob 31 has been turned 180°, one of the members 42 and 43 quickly springs from across the opening between the flanges 40 110 and 41 to permit the coin to be released then and then only.

A spring case 46 and a pointer 47 are mounted on a shaft 72 upon which a collar 48 is loosely mounted. A dial 49 is mounted 115 on the collar 48, and the inner end of the spring 26 is also operatively connected to the collar. The outer end of the spring 26 is connected to the spring case 46 one portion of which constitutes a gear wheel 50 that is adapted to engage a pinion 51 which is mounted on a rotatable and slideable shaft 52. The shaft 52 is provided with relatively long bearings 53 where it passes through the plate 22, and a clip 54 120 is provided for holding the shaft 52 in such position that the pinion 51 normally engages the gear wheel 50. When the clip 54 125 is removed from the position shown in Fig. 5 of the drawings, the shaft 52 may be so 130

5 moved that the pinion 51 does not engage the gear wheel 50, and the spring 26 may unwind without restriction. The shaft 52 is shifted longitudinally when it is desired to test the coin-controlled device. A gear wheel 55 is also mounted on the shaft 52 and is adapted to engage a pinion 56 that is mounted on a shaft 57 upon which an escapement wheel 58 is also mounted. A 10 double palette 59 and an eccentric strap 61 are mounted on a shaft 60, and the eccentric strap 61 is adapted to surround an eccentric 62 that is mounted on a shaft 63 upon which a worm wheel 64 is also mounted. The worm wheel 64 is adapted to engage a worm screw 65 that is mounted on a shaft 66 upon which a gear wheel 67 is also mounted. The gear wheel 67 is adapted to engage a pinion 68 that is mounted on 15 the main shaft 8 of the meter 3. Thus, when the armature 7 of the meter 3 rotates, the oscillation of the double palette 59 caused by the coöperation of the eccentric 62 and the eccentric strap 61, will cause the spring 26 to 20 be unwound from its outer end in accordance with the speed of the armature 7.

25 The dial 49 is provided with gear teeth 69 on its outer edge that are adapted to engage an idler gear wheel 70, which, in turn, engages a pinion 71 that is mounted on the main shaft 39. A ratchet wheel 73 is mounted on the shaft 39 and is adapted to be engaged by a spring-pressed pawl 74 to prevent the spring 26 from being unwound 30 from its inner end.

35 A lever 75 is mounted on the collar 48 and is provided with two spaced-apart arms 76 and 77 that are adapted to engage lever arms 78 and 79, respectively. The lever arm 40 78 and a lever arm 81 are mounted on a shaft 80 that is supported by brackets 82 on one face of the gear wheel 50. The lever arm 79 is mounted on a shaft 83 upon which a lever arm 84 that extends through an 45 opening 85 in the shaft 72 is also mounted. The lever arms 78 and 79 extend through an opening in the spring case 46. A pin 86 is loosely disposed in the shaft 72 and is adapted to be pressed outwardly to engage one 50 arm of a spring-restrained pivoted member 87 when the spring 26 is so unwound that the arm 77 of the lever 75 engages the lever arm 79. An annular member 88 loosely surrounds the shaft 72 and constitutes a spring-restrained pivoted member having an arm 55 89 that is operatively connected to a pin 90 which is adapted to extend across the opening 29 in the casing 28 when the lever arm 81 is actuated. The lever arm 81 and, consequently, the arm 89 are actuated only 60 when the spring 26 is wound to such an extent that the arm 77 of the lever 75 engages the lever arm to rock the shaft 80. Since the annular pivoted member 88 is disposed 65 around the shaft 72, the arm 81 will engage

the same irrespective of the position of the spring case 46.

A mutilated or segmental gear wheel 91 is mounted on one end of the shaft 39 and is adapted to engage a mutilated or segmental pinion 92 that is mounted on a pivoted member 93. The pivoted member 93 is provided with a bridging contact member 94 that is adapted to complete the circuit between two stationary contact members 95 and 96. The stationary contact members 95 and 96 are mounted on an insulating member and are provided with binding screws 97 for attaching the respective conductors of the meter windings thereto. The movable member 93 is provided with a spring 98 that is adapted to snap the bridging contact member 94 into and out of engagement with the stationary contact members 95 and 96. A pin 99 is mounted on the movable member 93 and is adapted to engage one arm of the spring-restrained pivoted member 87 for the purpose of holding the bridging contact member 94 in its closed position until the spring 26 is sufficiently unwound to permit the lever arm 75 to rock the shaft 83.

When a coin that is inserted in the slot 17 becomes wedged between the plates 34 and 38 and the knurled head knob 31 is rotated 180°, the dial 49 will be moved a predetermined distance, and the spring 26 will be wound a corresponding amount from its inner end. When the knob 31 is being turned to wind the spring, the mutilated gear wheel 91 engages the mutilated pinion 92, which is now in such position that the contact members 94, 95 and 96 are disengaged, and causes the movable member 93 to be moved to such position that the spring 98 snaps the bridging member 94 into engagement with the stationary contact members 95 and 96. It is held in this position by the engagement of one arm of the pivoted member 87 with the pin 99. When the switch is closed, the armature 7 of the meter 3 rotates to actuate the escapement mechanism 25, which permits the spring 26 to be unwound from its outer end and the pointer 47 to be moved in the same direction that the dial 49 was moved. Thus, when the pointer reaches the position, with respect to the dial, that it originally had, the lever 75 will move the lever arm 79, which, in turn, will cause the lever arm 84 to actuate the pivoted member 87 to release the movable member 93. When the member 93 is released, it will quickly snap into such position that the circuit of the meter windings will be opened. Since the lever arm 84 is so disposed as to operate a pin located in the center of the shaft 72, it is immaterial what the position of the spring drum 46 is, because the active length of the lever arm of the pivoted member 87 is always the same.

If sufficient coins are inserted through the

130

coin slot 17, and the knurled head knob 31 is turned until the winding of the spring 26 causes the lever 75 to engage the lever arm 78, the lever arm 81 will engage the pivoted member 88 to cause the pin 91 to close the slot 29. When the spring 26 unwinds, the movement of the lever 75 causes the lever arm 78 and, consequently, the pin 90, to be so moved that more coins may be inserted in 10 the opening 29 when the spring has been unwound an amount equivalent to the amount that it is wound for each coin.

It will be understood that our invention is not limited to the specific structure illustrated, but is adaptable to various modifications without departing from the spirit and scope of the invention as set forth in the appended claims.

We claim as our invention:

20 1. A controlling device comprising a switch, a rotatable member, a spring operatively connected to the rotatable member, a pin loosely mounted in the rotatable member and means for coöperating with the pin to trip the switch when the spring is unwound a predetermined amount.

25 2. A controlling device comprising a switch, a spring-actuated rotatable member, a pin loosely mounted in the rotatable member and means for coöperating with the pin to trip the switch under predetermined conditions.

30 3. A coin-actuated device comprising a casing having diametral openings therein, a spring-restrained disk pivoted in one end of the casing and having coin-positioning projections in its face and a peripheral flange with an opening therein, a second rotatable disk having a peripheral flange with diametral openings therein, two resiliently mounted members mounted on the second disk and a pin adapted to coöperate with the resiliently mounted members to maintain the opening in the flanged periphery of the 40 spring-restrained disk closed until it has been turned a predetermined distance.

45 4. A coin-actuated device comprising an actuating member having an opening therein, an actuated member adapted to grip a coin disposed between it and the actuating member, resiliently mounted members operatively connected to the actuated member and a pin adapted to restrain the resiliently mounted members across the opening in the actuating member until it has been rotated a predetermined distance.

50 5. A controlling device comprising a switch, a rotatable member, a spring having one of its ends connected to the rotatable member, a pin loosely mounted in the rotatable member and means mounted on the said rotatable member for coöperating with the pin to trip the switch under predetermined conditions.

6. A controlling device comprising a 65 switch, a rotatable member, a spring having one of its ends connected to the rotatable member, a pin loosely mounted in the rotatable member and means mounted on the said rotatable member for coöperating with the pin to trip the switch when the spring has been unwound a predetermined amount.

7. A controlling device comprising a switch, a rotatable member, a spring having one of its ends connected to the rotatable 75 member, a pin loosely mounted in the rotatable member and means mounted on the said rotatable member for coöperating with the pin to trip the switch when the spring has been unwound a predetermined amount, 80 irrespective of the position of the said means.

8. A controlling device comprising a switch, a spring-actuated rotatable member, a pin loosely mounted in the rotatable member and means mounted on the rotatable member for coöperating with the pin to trip the switch under predetermined conditions.

9. A controlling device for a prepayment meter comprising a switch, a coin device, a 90 spring adapted to be wound by the coin device, means for permitting the unwinding of the spring, and means for closing the coin device and for tripping the switch when the spring has been wound a predetermined 95 amount and unwound a predetermined amount, respectively.

10. A controlling device comprising a switch, a spring-actuated rotatable member, a pin loosely mounted in the rotatable member and means mounted on the rotatable member for coöperating with the pin to trip the switch under predetermined conditions, irrespective of the position of the said means.

105 11. A controlling device for a prepayment meter comprising a switch, a coin-actuated device, a spring adapted to be wound from one end by the coin device, means for permitting the unwinding of the spring from 110 its other end, and means for closing the coin-actuated device when the spring has been wound a predetermined amount and for tripping the switch when the spring has been unwound a predetermined amount.

115 12. A controlling device for a prepayment meter comprising a switch, a coin-actuated device, a spring adapted to be wound from one end by the coin device, means for permitting the unwinding of the spring from its other end, and means for closing the coin-actuated device under predetermined conditions and for tripping the switch when the spring has been unwound a predetermined amount.

120 125 13. A controlling device for a prepayment meter comprising a switch, a coin device, a spring adapted to be wound by the actuation

of the coin device, and means for closing the coin device and for tripping the switch when the spring has been wound and unwound predetermined amounts, respectively.

5 14. In a prepayment meter, the combination with a switch, a coin-controlled device, and an actuating spring, of means for closing the coin-controlled device under predetermined conditions and for tripping the

switch when the spring has been unwound a 10 predetermined amount, irrespective of the position of the said means.

In testimony whereof, we have hereunto subscribed our names this 29th day of Feb., 1916.
